UNITED STATES PATENT OFFICE.

ERNEST WOOLLETT, OF CHICAGO, ILLINOIS, ASSIGNOR OF ONE-HALF TO FRED WHITFIELD AND JOSEPH H. WHITFIELD, BOTH OF CHICAGO, ILLINOIS.

VALVE.

1,118,992.

Specification of Letters Patent.

Patented Dec. 1, 1914.

Application filed May 15, 1909. Serial No. 496,273.

To all whom it may concern:

Be it known that I, ERNEST WOOLLETT, a citizen of the United States, residing at Chicago, State of Illinois, have invented 5 certain new and useful Improvements in Valves or the like, of which the following is a description.

My invention belongs to that class of devices known as valves or stop cocks or the 10 like and relates particularly to the valves for gas burners.

My invention has for its objects the production of a simple, safe, efficient and satisfactory device of the kind described at 15 comparatively small cost for use wherever found applicable.

To this end my invention consists in the novel construction, arrangement and combination of parts herein shown and described and more particularly pointed out in the claims.

In the drawings wherein like reference characters indicate like or corresponding parts, Figure 1 is a side elevation of any suitable form of gas stove or oven provided with my preferred form of valve, Fig. 2 is a front elevation of the same, Fig. 3 is a sectional view of the same taken substantially on line 3—3 of Fig. 4, Fig. 30 4 is a sectional view of the same taken substantially on line 4—4 of Fig. 3, Fig. 5 is a view in elevation of my preferred form of valve, Fig. 6 is a sectional view of the same, Fig. 7 is a plan view partly in section taken substantially on the line 7—7 of Fig. 5, Fig. 8 is a sectional view of a portion of the valve showing the ports open, and Fig. 9 is a sectional view taken substantially on line 9—9 of Fig. 6.

Referring to the drawings my preferred form of device is shown as applied to a gas stove oven, it being readily understood that it may be used on any desired form or design of stove oven or water heater or wherever it may be found applicable. The stove shown comprises the usual walls 1 and the usual partition 2 and doors 3 and 4, the burner 5 being arranged below the partition or wherever desired. The burner 50 is supplied with gas through the inlet pipe 6, any suitable form of mixer 7 being preferably provided.

My device is particularly arranged to control the gas admitted into the inlet pipe 55 6 to the mixer and burner, the preferred

construction comprising a pilot light which is lighted and then used to light the burner, it being impossible for the gas to flow to the burner until the pilot is in operative lighting position.

The device may be placed in any suitable location on the stove, as shown it is arranged at one corner and the pilot arranged to be turned through an opening or slot 33 to the burner.

The preferred construction of valve comprises a casing 9 provided with an inlet from the supply pipe 8 and an outlet 10, the passage of gas through the casing being controlled by a suitable valve member 11 or its equivalent. The valve member is provided with a chamber 12 open to the supply pipe 8 and with a port opening 13 to the outlet 10. In the preferred construction the valve member is extended as at 14 as will be more fully explained hereafter. The valve member may be arranged and secured in position in any suitable way, as shown the casing is slightly tapered as is also the valve member, the valve member 80 being retained in position by means of a washer 15 and nut 16. Any equivalent means may be employed for the purpose. The gas through the supply pipe passes through the chamber 12 in the valve member 9 through the port 13 into the burner inlet pipe 6 when the valve member is rotated so that the port 13 registers with the casing outlet 10 (see Fig. 8). As shown the port 13 and the casing outlet 10 are 90 preferably constructed in the form of slits so that the gas cannot flow into the pipe 6 and thence into the burner until the lighter is in operative position. The slits permit the valve to be opened wide almost 95 instantaneously instead of gradually. Any suitable means may be employed for limiting the movement of the valve members, as shown the casing is cut away as at 17 (Fig. 5) and a pin 18 arranged on the valve 100 member, the part cut out substantially representing the travel of the valve.

As before mentioned the valve member is extended as at 14 to form a casing for what may be termed an auxiliary valve member 105 or pilot valve member 19. The chamber 12 in the valve member 11 is extended as at 22 to the pilot valve member 19 which is provided with a port opening 23 to the chamber 24 in the valve member, the port 23 be- 110

ing arranged to register with the opening 22 when the pilot 25 is turned down to the position shown in Fig. 3. The auxiliary valve member may be of any suitable shape and design, as shown it is preferably tapered and arranged to fit in its casing, a suitable washer 20 and screw 21 or their equivalents for the purpose being provided to retain the same in position. The chamber 24 in the 10 auxiliary valve member 19 is connected to the pilot member 25 there being an opening 26 through the pilot member as shown. The pilot member may be of any suitable form or size, the same preferably comprising a 15 tube adapted to fit and be secured in the extended part 27 of the auxiliary valve member. Any suitable means may be employed for limiting the movement of the auxiliary valve member, as shown the part 14 is cut 20 out as at 28 and a suitable pin 29 arranged on the valve member and adapted to cooperate with the cut out portion and limit the movement of the valve.

When the pilot is in the position shown in 25 Figs. 1, 2, 5 and 6, the auxiliary valve member is in such a position that the port opening 23 does not register with the opening 22 in the other valve member so that no gas is admitted to the pilot. In the preferred construction it is desired that the main valve member 11 close the outlet 10 in the casing when the pilot is closed and that the main valve member be locked against rotation except when the pilot is turned down. To 30 lock the main valve in its closed position when the pilot is turned up I preferably provide a stop or flange 30 on the valve casing arranged to cooperate with the extension 31 on the pilot valve member 19 (see 35 Figs. 5, 6 and 7). The flange 30 on the casing is preferably extended around the casing some little distance as shown in Fig. 7, so that the pilot member can not be turned to the position shown in Figs. 5 and 6 unless the valve member is turned so that the extension 31 on the pilot will not interfere with the flange 30 on the casing. The extension on the pilot may be extended as 40 shown at 32 to form a handle for controlling 45 the movement of the pilot.

Assuming that the gas in the stove oven is to be turned on and it is desired to light the burner, the gas being turned off the pilot is in a position indicated in Figs. 1, 2, 55 5 and 6. To light the gas the pilot is turned down to the position indicated by the dotted lines in Fig. 4 which opens the pilot valve so that a match may be applied to the pilot and the same be thereby lighted. The pilot is 60 then turned in to the oven through the opening 33 so that it takes substantially the positions shown in Figs. 3 and 4 or within lighting distance of the burner. This opens the main valve so that gas is admitted through 65 the inlet pipe 6 and mixer 7 where it is im-

mediately lighted by the pilot light. In this construction both valves being controlled directly by the movement of the pilot, in bringing it down and swinging it inward there is no possibility of the burner not 70 being lighted provided the pilot is lighted and there can be no accumulation of gas in the oven, as for example, in the case where the two valves are independent and the main valve opened and then at some later time the 75 pilot turned to the burner. In this example mentioned the mixture of gas and air in the oven might be sufficient or such as to form an explosive mixture which would be set off by the pilot light. It might be noted that 80 the pilot might be provided with a small valve so that the pilot might be turned off after the burner has been lighted but this construction however is not necessary and is 85 preferably omitted. It might also be mentioned that in cases where gas is used for heating an oven in which the gas is turned on for a certain length of time heating a 90 plate or the equivalent of heat storing material and then the gas turned off and the 95 oven shut up, my device might be very aptly applied thereto in which case it might be passed through the door opening or the equivalent by which air is admitted for the burner while the heat is being stored. In 100 this case it would be impossible to close the door or opening, thereby closing the oven, if the pilot passed therethrough without turning off the gas thereby avoiding the danger of closing the opening and having 105 the gas burner extinguished for lack of air. This is merely mentioned as a use of the device when applied to another style of oven other than that shown. As before mentioned it might also be found very satisfactory when used on a water heater.

Having thus described my invention it is obvious that various immaterial modifications may be made in the form, arrangement and combination of parts without departing 110 from the spirit of my invention. Hence I do not wish to be understood as limiting myself to the exact construction, arrangement, combination of parts or uses mentioned, shown or described.

What I claim as new and desire to secure by Letters Patent is:

1. In a device of the kind described and in combination, a casing provided with an inlet and an outlet, a main valve member 120 controlling said outlet, an auxiliary outlet in said main valve, said auxiliary outlet provided with a valve member therefor, said auxiliary valve member carried by the main valve member and arranged to move and in 125 its movement to operate said main valve member.
2. In a device of the kind described and in combination, a valve casing provided with an inlet and outlet, a movable valve member 130

arranged therein, a movable pilot member carried by and operatively connected with and arranged to control said movable valve member, and a pilot operated by the movement of said pilot member.

5. In a device of the kind described and in combination, a fuel supply pipe, a main valve therefor, a pilot, an auxiliary valve therefor, said main and auxiliary valves 10 constructed and arranged to be controlled respectively by independent movements of said pilot in a plurality of directions.

6. In a device of the kind described and in combination, a movable pilot member, a controlling valve member therefor and operated thereby, and a main burner valve, said main burner valve carrying said controlling valve member and arranged to be controlled by said pilot member.

20. 5. In a device of the kind described and in combination, a casing provided with an inlet and outlet, a movable valve member arranged therein, a movable pilot member, and a valve for the pilot member said pilot member mounted upon the movable valve arranged to control both of said valve members.

6. In a device of the kind described and in combination, a fuel supply pipe, a movable pilot member, a movable valve member therefor controlled by movement thereof for establishing communication between the fuel supply pipe and the pilot member, and a main burner valve member for the fuel supply pipe controlled by a movement of said pilot member.

7. In a device of the kind described and in combination, a movable pilot member, a main valve member, and an auxiliary valve member, the auxiliary valve member controlled by a predetermined movement of said pilot and the main valve member controlled by a subsequent movement of said pilot.

45. 8. In a device of the kind described and in combination, a gas oven, a burner therefor and means for controlling the gas admitted to said burner, comprising a valve, a movable pilot member carried by and arranged to control said valve and means for controlling the admission of gas to said pilot member, also governed by the movement of the pilot member.

9. In a device of the kind described and 55 in combination, a pilot member arranged to move in a plurality of directions, a main valve and an auxiliary valve member controlled by said pilot, the auxiliary valve member controlled by movement of said pilot in one direction and the main valve member controlled by the further movement of said pilot member in a transverse direction.

10. In a device of the kind described and 65 in combination, a movable valve member,

a movable pilot member mounted upon and arranged to control said valve member and substantially instantaneously open the same when the pilot reaches its operative lighting position, and means for controlling the 70 gas admitted to said pilot, said means being controlled by the pilot member.

11. In a device for supplying gas to a main burner, the combination of a main valve, adapted to regulate the supply of gas 75 to the main burner, a pilot valve, said valves having transverse axes, and one of said valves constituting a carrying member for the other, whereby, by movement of one of the valves in one direction the other valve 80 is opened.

12. In a device of the kind described, a main burner, a pilot burner, a main valve for the main burner, a pilot valve for the pilot burner, said valves having an inter- 85 communicating passage way, adapted to be brought into registration by movement of the pilot valve in one direction thereby opening the same, and a further movement of the pilot valve in a transverse direction 90 will open the main valve.

13. In a device of the kind described, a main valve, a pilot valve, said valves having an intercommunicating passageway, adapted to be brought into registration by a 95 movement of the pilot valve in one direction thereby opening the same, and a subsequent movement of the pilot valve will open the main valve, and an operating handle carried by the pilot valve.

14. In a device of the kind described, a main valve, a pilot valve, said valves having an intercommunicating passageway adapted to be brought into registration by movement of the pilot valve in one direction, thereby opening said pilot valve, and a subsequent movement of the pilot valve in a transverse direction will open the main valve, and an operating handle carried by the pilot valve.

15. In a device of the kind described, the combination of a main valve, a burner supply pipe, a pilot member, and means whereby the main valve will shut off the supply through said pipe until after a distinct 115 movement of the pilot member.

16. In a device of the kind described, the combination of a burner supply pipe a main valve therefor, a pilot member, and means whereby the main valve will shut off the 120 supply through said pipe until after a distinct movement of the pilot member in a transverse direction.

17. In a device of the character described, the combination of a supply pipe having a 125 laterally extending outlet, a rotary valve having a longitudinal opening therethrough and a communicating opening for registering with the outlet, and a pilot light member having an extension rotatably mounted 130

- upon the rotary valve for movement therewith and having an opening adapted to register with the longitudinal opening of the rotary valve.
18. In a device of the character described, the combination of a supply pipe having a transverse outlet, a main rotary valve having a longitudinally extending opening therethrough and a communicating transverse opening for registering with the outlet, a pilot light member having a transverse extension rotatably mounted upon the main rotary valve for movement therewith and having an opening adapted to register with the longitudinal opening of the rotary valve, and means for preventing opening movement of the rotary valve until after a predetermined rotary movement of said transverse extension.
19. In a device of the character described, the combination of a main burner supply pipe, a main valve therefor, a pilot valve mounted thereon for rotary movement, and means for preventing the operation of the main valve to supply said pipe until after a predetermined movement of the pilot valve in a transverse direction.
20. In a device of the character described and in combination, a supply pipe, a main valve therefor, a pilot, an auxiliary valve therefor, said auxiliary valve carried by the main valve and adapted to control the operation of the main valve.
21. In a device of the character described and in combination, a supply pipe, a main valve therefor, a pilot, an auxiliary valve therefor, said auxiliary valve carried by the main valve and arranged to be rotated then moved in a transverse direction to operate the main valve.
22. In a device of the character described and in combination, a supply pipe, a main valve therefor, a pilot, an auxiliary valve therefor, said auxiliary valve carried by the main valve and arranged to be rotated to open said auxiliary valve and subsequently move in a transverse direction to operate the main valve.
23. In a device of the character described and in combination, a supply pipe, a main valve therefor, a pilot, an auxiliary valve therefor, said auxiliary valve mounted transversely upon the main valve and swung as a means for operating the main valve.
24. In a device of the kind described and in combination, a casing provided with an inlet and an outlet, a main valve member controlling said outlet, said valve member provided with an auxiliary outlet, and an auxiliary valve controlling said auxiliary outlet, said auxiliary valve arranged to move, and in its movement, control both the main valve and the auxiliary outlet.
25. In a device of the kind described and in combination, a casing provided with an
- inlet and an outlet, a main valve member controlling said outlet, said valve member provided with an auxiliary outlet, and an auxiliary valve mounted in said valve member controlling said auxiliary outlet, said auxiliary valve arranged to move, and in its movement, control both the main valve and the auxiliary outlet. 70
26. In a device of the kind described and in combination, a casing provided with an inlet and an outlet, a main valve member controlling said outlet, said valve member provided with an auxiliary outlet, and an auxiliary valve rotatably mounted in said valve member controlling said auxiliary outlet, said auxiliary valve arranged to move, and in its movement, control both the main valve and the auxiliary outlet. 75
27. The combination with a supply pipe having a transverse outlet, a main valve having a transverse bore in its end, a longitudinal opening extending from said bore to the inlet end of said valve, a transverse port in said main valve in communication with the longitudinal opening and adapted for registration with the said outlet, and an auxiliary valve mounted in said bore, provided with a port adapted for registration with the said longitudinal opening in the main valve. 80
28. In a device of the character described, the combination of a fuel supply pipe, a valve casing communicating therewith and having an outlet opening, a main valve adapted to establish communication between said supply and outlet, said valve member provided with an auxiliary outlet, an auxiliary valve adapted to be placed in communication with said auxiliary outlet, and means preventing movement of the main valve to establish communication between the supply and outlet until the auxiliary valve has first been moved to communicate with the auxiliary outlet. 85
29. The combination with a supply pipe, a casing connected thereto provided with an outlet, a main valve having a transverse bore in its end, a longitudinal opening extending from said bore to the inlet end of said valve, a transverse port in said main valve in communication with the longitudinal opening and adapted for registration with the said outlet, an auxiliary valve mounted in said bore, provided with a port adapted for registration with the said longitudinal opening in the main valve, and a pilot member connected to said auxiliary valve. 90
30. The combination with a supply pipe, a casing connected thereto provided with an outlet, a main valve having a transverse bore in its end, a longitudinal opening extending from said bore to the inlet end of said valve, a transverse port in said main valve in communication with the longitudinal opening and adapted for registration 120
- 130

with the said outlet, an auxiliary valve mounted in said bore, provided with a port adapted for registration with the said longitudinal opening in the main valve, said auxiliary valve provided with an extension, and a pilot member connected to said extension.

31. The combination with a supply pipe, a casing connected thereto provided with an outlet, a main valve having a transverse bore in its end, a longitudinal opening extending from said bore to the inlet end of said valve, a transverse port in said main valve in communication with the longitudinal opening and adapted for registration with the said outlet, an auxiliary valve mounted in said bore, provided with a port adapted for registration with the said longitudinal opening in the main valve, and a pilot member connected to said auxiliary valve.

32. In a device of the character described, the combination with a fuel supply pipe, a casing connected thereto provided with an outlet, a main valve in said casing adapted to establish communication between the supply pipe and the outlet, an auxiliary outlet through said main valve, an auxiliary valve controlling said auxiliary outlet, and means upon said casing, main and auxiliary valves for preventing the operation of the main valve until after a predetermined movement of the auxiliary valve.

33. In a device of the kind described, in combination with a fuel supply pipe, a casing connected thereto and provided with

an outlet, a main valve in said casing adapted to establish communication between the supply pipe and the outlet, a stop pin on the main valve, an auxiliary outlet through said main valve, an auxiliary valve controlling said auxiliary outlet, an operating handle upon said auxiliary valve, and means upon the casing acting in conjunction with the handle upon the auxiliary valve and the pin upon the main valve, thereby preventing the movement of the main valve until after a movement of the auxiliary valve.

34. In a device of the character described, in combination with a fuel supply pipe, a casing connected thereto and provided with an outlet, said casing provided with a cut-away portion, a flange on said casing, a main valve in said casing adapted to establish communication between the supply pipe and the outlet, said main valve provided with a stop pin arranged in the cutaway portion, an auxiliary outlet through said main valve, an auxiliary valve member controlling said auxiliary outlet, and means connected to said auxiliary valve member abutting against said flange thereby preventing the operation of the main valve until after a movement of the auxiliary valve.

In testimony whereof, I have hereunto signed my name in the presence of two subscribing witnesses.

ERNEST WOOLLETT.
